J. E. SCOTT.
SALT CELLAR.
APPLICATION FILED SEPT. 20, 1921.

1,424,040.

Patented July 25, 1922.

Inventor
John E. Scott
Williamson

UNITED STATES PATENT OFFICE.

JOHN E. SCOTT, OF PHILADELPHIA, PENNSYLVANIA.

SALTCELLAR.

1,424,040.

Specification of Letters Patent. **Patented July 25, 1922.**

Application filed September 20, 1921. Serial No. 501,957.

To all whom it may concern:

Be it known that I, JOHN E. SCOTT, a citizen of the United States, residing at Philadelphia, in the county of Philadelphia and State of Pennsylvania, have invented new and useful Improvements in a Saltcellar, of which the following is a specification.

My invention relates to new and useful improvements in salt cellars, and has for its object to provide an exceedingly simple and effective construction which will prevent the clogging of the salt at the point of delivery from the cellar.

15 A further object of the invention is to provide for the proper stirring and breaking up of the salt and also to close the cellar against the outflow of salt and the intaking of moisture.

With these ends in view, this invention
20 consists in the details of construction and
combination of elements hereinafter set forth
and then specifically designated by the
claims.

In order that those skilled in the art to
25 which this invention appertains, may understand how to make and use the same, I will
describe its construction in detail, referring
by numerals to the accompanying drawings
forming a part of this application, in
30 which:—

Fig. 1, is a side elevation of a salt cellar made in accordance with my improvement.

Fig. 2, is a central vertical section of a portion of the cellar showing the agitator carried by the regulating disc.

Fig. 3, is a section at the line 3—3 of Fig. 1.

Fig. 4, is a side elevation of the agitator taken at right angles to Fig. 2.

40 In carrying out my invention as here embodied, 1 represents a salt cellar which may be of any design or size and 2 represents the cap which may be secured upon the open end of the cellar in any suitable manner, here 45 shown as being threaded thereon and in the edge of this cap is formed an outlet slot 3 through which the contents of the cellar may be shaken.

4 represents a regulating disc which is pivoted at 5 to the top of the cap and this disc

is here shown as of segmental shape, the curved periphery of which lies in close proximity or contact with the inner surface of the side wall of the cap so as to be drawn back and forth over the delivery slot 3 for opening or closing said slot as clearly shown in Fig. 3.

The segmental disc 4 has an extension or thumb piece 5' which projects through the slot 3 in order that the regulating disc may be readily moved back and forth to open or close the delivery slot. 60

6 represents an agitator which is here shown as formed with the segmental regulating disc 4. This agitator has a series of wings 7 projecting therefrom so that should the salt become packed or hardened in the cellar it may be broken up by manipulating the thumb piece 5' so as to oscillate the agitator. 65 70

As is well known the contents of the salt cellar becomes damp by absorbing the moisture from the atmosphere after which it will clog the usual perforations through which it is to be shaken so that no salt can be delivered without removing the cover but by my improvement the oscillating of the thumb piece will not only stir and loosen the salt in the cellar but will also keep the delivery slot clear of any obstruction, thereby permitting the free delivery of the salt through said slot. Another advantage of my improvement is that the salt will be delivered in a dry condition.

ment is that the segmental disc 4 may be set at any position relative to the delivery slot 3 thereby increasing or decreasing the opening through which the salt is to be delivered and also when the device is not in use the delivery slot 3 may be entirely closed, thus preventing the access of moisture to the contents of the cellar. 90

Of course I do not wish to be limited to the exact details of construction as herein shown as these may be varied within the limits of the appended claim without departing from the spirit of my invention.

Having thus fully described my invention, what I claim as new and useful is:—

In a salt cellar, a receptacle, a cover therefor having a segmental delivery slot in the side thereof, a quadrant-shaped metallic 100

member pivoted to the under side of the central portion of the cover and including an offset portion movable through the slot and acting as an operating member and a slot cleaner, the edge portion of the plate being in the plane of the delivery slot and adapted to close the latter, and an agitator formed with the metallic plate and constituting a

strip projecting downwardly therefrom, said agitator including angular cutting blades deflected laterally in various directions by bending the metal of which the strip is formed. 10

In testimony whereof, I have hereunto affixed my signature.

JOHN E. SCOTT.
